UNITED STATES PATENT OFFICE.

JULIUS DEBORDE, OF BERLIN, GERMANY.

ELASTIC FILLING MATERIAL FOR CYCLE-TIRES, &c.

SPECIFICATION forming part of Letters Patent No. 617,230, dated January 3, 1899.

Application filed April 22, 1897. Serial No. 633,393. (No specimens.)

To all whom it may concern:

Be it known that I, JULIUS DEBORDE, a citizen of the German Empire, residing at Berlin, in the Kingdom of Prussia, German Empire, have invented certain new and useful Improvements in the Manufacture of Elastic Fillings for Cycle-Tires, Saddles, Cushions, &c., (for which Letters Patent have been granted to me in Germany, No. 95,260, dated 5 March 11, 1897; in Sweden, No. 8,232, dated April 9, 1897; in France, No. 265,897, dated April 10, 1897; in Belgium, No. 127,515, dated April 10, 1897; in England, No. 8,905, dated April 7, 1897; in Austria, No. 2,450, dated 10 April 9, 1897; in Norway, No. 6,042, dated June 8, 1897; in Hungary, No. 9,726, dated June 15, 1897; in Switzerland, No. 14,777, dated June 4, 1897; in Italy, No. 44,956, dated June 30, 1897; in Luxemburg, No. 2,867, 15 dated June 4, 1897, and in Spain, No. 20,995, dated June 11, 1897,) of which the following is a specification.

This invention relates to an improved elastic filling or padding for tires of all kinds, 20 saddles, cushions, &c.; and the invention consists of a filling for tires, &c., consisting of a spongy jelly-like substance formed, essentially, of a glue solution that is changed by mechanical treatment into a foamy condition.

25 In the accompanying drawings, Figure 1 is a vertical transverse section through a bicycle-saddle, the cushion of which is made of the improved material forming the subject-matter of this invention; and Fig. 2 is a vertical transverse section of a tire which is filled with 30 my improved elastic material.

Referring to the drawings, *a* in Fig. 1 represents the filling of a saddle pad or cushion of suitable shape, *c* the saddle-base, and *b* 35 the covering.

In Fig. 2, *z* represents the wheel-rim, upon which is secured the tire, having an outer portion *v*, an inner portion *s*, and a filling *a* of my improved material.

40 In making my improved filling for tires and other articles the filling is formed from a suitable jelly or other glue-like substance which has been transformed into a spongy condition. For this purpose a jelly of glue, gelatin, or 45 like substance, or a mixture of glue with other substances is liquefied by heat and beaten up while in liquid condition by means

of agitators, stirrers, centrifugal apparatus, or otherwise into foam. This foam is applied 55 into tires, cushions, or other articles formed of leather, soft rubber, oil-cloth, or other suitable material and then converted into a rigid state by cooling. After cooling the foam-like jelly appears to be permeated by a very large 60 number of small cavities filled with air, by which the elasticity of the mass, which in itself is elastic, is considerably increased and the weight of the same diminished.

To prevent the hardening of the jelly, especially when same is made from glue or gelatin, glycerin is added, and in addition thereto 65 to an antiseptic substance, by which the fermentation can be prevented. In place of forcing the spongy mass directly into tires, cushions, and other objects the same can first be 70 cast in suitable forms which can be, after cooling, transferred into a suitable sheath of soft leather or other material. The elasticity and the small weight of the objects which are filled in this manner with foam-jelly can be still 75 more increased when a number of small balls of soft rubber and rubber tubes or hollow elastic bodies are introduced into the mass before the cooling of the same.

The foam-jelly, which is produced in the 80 manner herein described, can also be used to advantage as a filling for the tires of vehicles, saddles, handles, and cushions of all kinds. These cushions are durable, do not become 85 rigid, non-elastic, or hardened, and can be manufactured at a considerably small expense. One of the advantages of the same is that they are good conductors of heat, and consequently quite cool in use.

Having thus described my invention, I 90 claim as new and desire to secure by Letters Patent—

1. An elastic filling for tires, saddles, cushions and other articles, consisting of a spongy foam-jelly formed of a mixture of gelatin 95 and glycerin, substantially as set forth.

2. An elastic filling for tires, saddles, cushions and other articles, consisting of a spongy foam-jelly formed of a mixture of gelatin, glycerin and an antiseptic substance, substantially as set forth.

3. The process herein described of making a sponge-like filling for tires, saddles, cushions and other articles, which consists in sub-

jecting a mixture of gelatin and glycerin to mechanical agitation whereby it is changed into foam, casting or forming the same into suitable shape and cooling the same, substantially as set forth.

4. The process herein described of making a sponge-like filling for tires, saddles, cushions and other articles, which consists in subjecting a mixture of gelatin and glycerin to mechanical agitation whereby it is changed into foam, introducing therein hollow elastic

bodies, casting or forming the mass into suitable shape, and cooling the same, substantially as set forth.

In testimony that I claim the foregoing as my invention I have signed my name in presence of two subscribing witnesses.

JULIUS DEBORDE.
